UNITED STATES PATENT OFFICE

100,949

DESIGN FOR AN AUTOMOBILE TIRE

Harry C. Hower, Chicago, Ill.

Application June 6, 1936, Serial No. 63,058

Term of patent 7 years

To all whom it may concern:

Be it known that I, Harry C. Hower, a citizen of the United States, residing at Chicago, in the county of Cook and State of Illinois, have invented a new, original, and ornamental Design for Automobile Tires, of which the following is a specification, reference being had to the accompanying drawing, forming a part thereof.

In the drawing:

Figure 1 is a perspective view, partially in dotted lines, of a tire showing my new design; and

Figure 2 is fragmentary side elevational view of the tire shown in Figure 1, showing said design in said elevation on an enlarged scale.

I claim:

The ornamental design for an automobile tire, as shown.

In witness whereof, I hereunto subscribe my name this 3rd day of June, 1936.

HARRY C. HOWER.
